TOOL STOCK

William E. Cowley, Louisville, Ky., assignor to Vermont American Corporation, a corporation of Kentucky

Filed Dec. 14, 1959, Ser. No. 58,644

Term of patent 14 years

(Cl. D54—4)

The dominant features of the design reside in the portions shown in full lines.

I claim:

The ornamental design for a tool stock, substantially as shown and described.
